Primary Examiner—Lucy Lieberman

[57] CLAIM

The ornamental design for an angel doll, as shown and described.

DESCRIPTION

FIG. 1 is a front view of the angel doll of the present invention;

FIG. 2 is a back view of the angel doll of FIG. 1;

FIG. 3 is a left side view of the angel doll of FIG. 1; and, FIG. 4 is a right side view of the angel doll of FIG. 1.

The bottom of the angel doll and the portions of the top of the angel doll that are not shown in the drawings do not form part of the claimed design.
